(57) CLAIM

The ornamental design for a faucet handle, as shown and described.

DESCRIPTION

FIG. 1 is a front perspective view of a faucet handle showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a front perspective view of the faucet handle of FIGS. 1-6 shown as part of a disclaimed faucet assembly. The broken line showing of the remainder of the faucet assembly in FIG. 7 is for environmental purposes only and forms no part of the claimed design.
